UNITED STATES PATENT OFFICE

102,771

DESIGN FOR AN ASHTRAY

Harvey O. Walker, Los Angeles, Calif.

Application November 10, 1936, Serial No. 65,834

Term of patent 3½ years

To all whom it may concern:

Be it known that I, Harvey O. Walker, a citizen of the United States, residing at Los Angeles, in the county of Los Angeles and State of California, have invented a new, original, and ornamental Design for an Ashtray, of which the following is a specification, reference being had to the accompanying drawing, forming part thereof.

I claim:—

The ornamental design for an ashtray as shown.

HARVEY O. WALKER.
